US00D879651S

(12) **United States Design Patent** (10) Patent No.: **US D879,651 S**
(45) Date of Patent: **** Mar. 31, 2020**

(54) **DIAMOND**

(71) Applicant: **LUCKY EYE LIMITED**, Hong Kong (HK)

(72) Inventor: **Roni Rydlewickz**, Ho Chi Minh (VN)

(73) Assignee: **LUCKY EYE LIMITED**, Hong Kong (HK)

(**) Term: **15 Years**

(21) Appl. No.: **29/671,438**

(22) Filed: **Nov. 27, 2018**

(30) **Foreign Application Priority Data**

May 28, 2018 (EM) 005284783-0001

(51) LOC (12) Cl. **11-01**

(52) U.S. Cl.

USPC **D11/90**

(58) **Field of Classification Search**

USPC D11/1, 2, 16, 26–29, 34, 35, 36, 89–92
